UNITED STATES PATENT OFFICE

ERNEST L. NELSON, OF CHICAGO, ILLINOIS, ASSIGNOR TO BELDEN MANUFACTURING COMPANY, OF CHICAGO, ILLINOIS, A CORPORATION OF ILLINOIS

BROOM

Application filed July 20, 1927. Serial No. 207,029.

This invention relates to brooms and more particularly to a novel head therefor, especially for that type of broom having a long brush head with relatively short tufts, though 5 not limited to this particular type of brooms.

The object of the invention is to provide a broom having a head by which particles, including fine dust, may be swept or flipped along at each sweeping movement of the 10 broom, the head having a surrounding or encircling row of bristles forming the brush head proper, with a central longitudinal open space or pocket opening downwardly, in which is disposed a rubber or similar flexible strip or sheet fitting the inner wall of the 15 bristles, suitably secured to the head, together with resilient means tending to hold or spring the spaced portions of the flexible strip apart and against the inner sides of the 20 bristles forming the brush head proper so as to assist the latter in the sweeping action to insure that the dirt will be carried along instead of sifting through the bristles.

Other and further objects of the invention 25 will be apparent as the description proceeds.

In the accompanying drawings:—

Fig. 1 is a longitudinal sectional view of a broom embodying my invention.

Fig. 2 is a bottom view on a smaller scale, 30 and

Fig. 3 is a cross-sectional view taken on the section line 3—3 of Figure 1.

Referring to the drawings in detail, 4 designates the head of the broom, which is shown 35 of the usual brush type having opposite sockets 5 screw threaded or otherwise provided for the attachment of the handle (not shown). Attached to the head 4 in the usual or any preferred way are the bristles 40 or tufts 6, constituting the brush head proper, but in the present instance, arranged around the outer portion and extending from the bottom of the wooden or other head or body portion 4, so as to provide a surrounding brush 45 head of bristles with a central longitudinal open space or pocket 7 opening downwardly.

Within this space or pocket 7 is disposed a flexible and resilient sheet or wall 8, such as 50 rubber, the same being folded or bent on itself in curved formation as indicated at 9, so as to

provide a bight extending longitudinally and secured to the bottom face of the head 4 between the opposite portions or surrounding row of bristles by suitable fastenings, such as screws 10. Preferably, a strip 11 of wood or other rigid material is laid against the bent portion and, if desired, a plurality of expanding members 12 which may be seated in grooves or recesses in the strip 11 is disposed between the strip 11 and the bent or bight portion 9, all being apertured to receive the fastenings 10 for anchoring the parts to the head. The expanding members 12 are preferably made up of strips of flexible vulcanized rubber reinforced with embedded metal members 55 or wires 13 of flat, round, or other suitable cross-section, tending to normally expand the U-shaped members 12 against the inner faces of the folded sheet or strip 8 to hold the latter separated and against the inner faces of 60 the bristles. It is also to be understood that the resilient sheet 8 may be simply a flat sheet folded on itself or made continuous with the ends 14 if desired, although these ends are 65 preferably tapered to conform to the taper of the broom part 6, as clearly shown in Figure 70 2 of the drawings. It also will be noted that the free or bottom edges of the flexible sheet 8 extend to the bottom of the bristles, while the expanding members 12 preferably terminate a considerable distance above said 75 edges in spaced relation thereto.

With a broom such as described, the broom or brush head constituting the tufts or hairs composing the same, will act in the usual way, but particles, including fine dust, may be swept or flipped along at each sweeping movement of the broom owing to the flexible springy and flipping action of the sheet member 7, instead of the particles or dust sticking to the bristles or sifting through the same and necessitating that the sweeping movement be repeated several times in order to advance or carry along the particles, particularly the finer particles or dust. In other words, as the sweeping movement is effected, the bottom edges of the resilient or flexible sheet 8 of rubber or similar material will engage the ground or floor surface and at each 80 sweeping movement in either direction will 85 90 95 100

be sprung back and then released or flipped upon the pressure being relieved from the handle and broom as the latter is advanced and raised from the surface being swept, to be brought back for another brushing movement in the usual manner.

The expanding members 12 add to the effective action of the resilient walls 7 and tend to stiffen the same so as to prevent these walls from closing against each other and thereby assist in the movement of the dirt.

While I have described the sheet or flexible member 8 as being of rubber and also the expanding members 12, it is to be understood that any other suitable resilient material may be employed so long as the members 8 are made to flex and flip the dirt and not mar the floor surface. The expanding members 12 may be suitable spring members with or without the rubber covering.

While I have shown and described my invention in a preferred form, I am aware that various changes and modifications may be made therein without departing from the principles of the invention, the scope of which may be determined by reference to the appended claims.

I claim as my invention:

1. A broom including a body having a brush head with an intermediate open space, a resilient sheet set in said space against the inner face of the brush head and comprising opposite spaced walls disposed against the inner sides of the brush head and extending to the bottom of the brush head to contact with the surface being swept to flip dust and other particles along in sweeping.

2. A broom including a body having a brush head with an intermediate open space encircled by the brush head, a resilient sheet set in said space and comprising opposite walls secured to the body, said walls diverging downwardly in spaced relation against the inner faces of the bristles of the broom head to the bottom thereof and constituting means for flipping dirt and fine particles of dust in the use of the broom.

3. A broom including a head with a surrounding row of bristles providing an intermediate open space or pocket encircled by the bristles, a flexible rubber sheet secured to the head within and extending entirely around said pocket and against the inner face of the bristles, said sheet expanding against the inner sides of the bristles and having its entire bottom edge in line with the ends of the bristles.

4. A broom or brush including a head with a surrounding row of bristles providing an intermediate open space or pocket, a substantially U-shaped flexible sheet secured at the bight portion to the head within said pocket, and a plurality of reinforcing and resilient expanding members anchored to the head through said bight portion within said space

and acting against opposed portions of the sheet.

5. A broom including a head with a face having a peripheral row of bristles providing an intermediate open space or pocket, a flexible sheet secured to the head within and surrounding said pocket and having the edges thereof extending to the ends of the bristles of the head, said sheet being imperforate, resilient expanding members set within said sheet, and a strip with attachment means securing the sheet and expanding members to the body of the broom.

6. A broom including a head with a face having a peripheral row of bristles providing an intermediate open space or pocket, a flexible sheet secured to the head within and surrounding said pocket and having the edges thereof extending to the ends of the bristles of the head, resilient expanding members set within said sheet, and a strip with attachment means securing the sheet and expanding members to the body of the broom.

7. A broom including a head with a surrounding row of bristles providing an intermediate open space or pocket, a flexible sheet of substantially inverted V-shaped cross section secured to the head within said pocket, said sheet having its bottom edges contiguous with the free ends of the bristles, and expanding means secured to the bottom of the head within said space and acting outwardly against the inner face of said sheet to hold the same against the bristles.

8. A broom including a head with a face having a peripheral row of bristles providing an intermediate open space or pocket, and a resilient and flexible sheet folded and secured at the folded portion to the head within and surrounding said pocket to cause the opposite spaced portions of the sheet to press outwardly against the entire inner face of the row of bristles and having the edges thereof extending to the free ends of the bristles of the head to flip dirt along.

9. A broom including a head with a face having a peripheral row of bristles providing an intermediate open space or pocket, a flexible and resilient sheet secured to the head within and surrounding said pocket and having downwardly diverging sides the bottom edges thereof extending to the free ends of the bristles of the head to flip dust and other particles along in sweeping, a strip inserted between the diverging sides, and means to secure said strip and sheet to the body of the broom.

10. A broom of the class described including a head with a peripheral row of bristles anchored to and extending therefrom to provide an intermediate open space enlarging toward the free ends of the bristles, a flexible resilient sheet folded on itself and anchored at the fold to the head with its sides normally diverging downwardly and under

5 tension to cause the depending portions of the sheet to expand outwardly against the surrounding row of bristles, said sheet having its bottom edge extending to the free ends of the
5 bristles to engage the surface acted on in sweeping.

10 11. A broom including a head with a face having a peripheral row of bristles providing an intermediate open space, a flexible sheet secured to the head within and surrounding said space and having the edges thereof extending to the ends of the bristles, expanding members within said flexible sheet and acting outwardly against the same, a rigid
15 strip fitting against the sheet at the intermediate open space, said strip having grooves receiving the expanding members, and fastening means extending through the strip and into the head to secure the sheet and expanding members in position.
